UNITED STATES PATENT OFFICE.

CHRISTIAN SCHILLINGER, OF SCRANTON, PENNSYLVANIA.

BOILER FURNACE.

Application filed July 14, 1926. Serial No. 122,298.

My invention relates to boiler furnaces having traveling grates, and further relates to a method of promoting combustion in a furnace of this character.

5 Stoker manufacturers frequently are asked to submit proposals covering traveling or chain grate stokers for installation under old boilers that were set very low. In most cases, however, the cost of raising the boiler 10 or the possible lowering of the floor in order to provide room to install the stoker beneath the boiler is so high as to make the installation prohibitive, and in many instances it is 15 impossible to do either because of structural difficulties. In some instances this type of stoker has been installed under low set boilers with standard furnace arrangement, but invariably the installation has proved 20 inefficient, particularly when burning the finer grades of anthracite, and it was not possible to obtain very high ratings.

One of the objects of the present invention is to provide a furnace structure embodying a traveling or chain grate stoker 25 which is adapted to be installed in front of the boiler setting so as to make it unnecessary to either raise the boiler or lower the floor, and which is simple in construction, and of high efficiency and great flexibility, 30 and in which complete combustion is insured together with very low ash pit loss.

Another object of the invention is to provide a novel and improved method of promoting combustion which is particularly 35 adapted for use with traveling or chain grate stokers.

The several features of the invention, whereby the above mentioned and other objects may be attained, will be clearly understood from the following description and accompanying drawing in which the figure 40 is a longitudinal sectional view, partly diagrammatical, of my improved furnace structure.

45 My improved furnace structure, as illustrated in the drawing, is particularly adapted for use with an old boiler where it is desired to substitute a traveling or chain grate stoker for the stoker previously used. The 50 combustion chamber of the stoker is indicated at 2 and the chamber of the boiler is indicated at 4. The stoker may be of the usual construction having a chain grate 6, and a plurality of air supply compartments 8 arranged between the runs of the chain for supplying air under pressure to the up-

per run, the air supplies to the several compartments being separately controlled.

As shown, the traveling grate is arranged in front of the boiler chamber with its rear end spaced a distance from the front wall of said chamber to provide a space through which the ashes may be discharged from the grate. The combustion chamber is provided with a front wall 10 and a horizontally arranged top wall or roof 12 extending to the front wall of the boiler chamber. The front wall 10 of the combustion chamber is vertically arranged and its lower portion is inclined downwardly and forwardly to provide an ignition arch 14 extending to the upper edge of the fuel receiving opening 16, a fuel hopper 18 being provided which leads into said opening.

70 The combustion chamber is further provided with a rear arch 20 which extends from the front wall of the boiler chamber over a little more than one-half the length of the grate. The underside of the rear arch is inclined upwardly and forwardly with its rear end portion arranged in proximity to the grate. The forward end of the underside of the arch is curved in an arc to the front end of the arch which extends upwardly a distance parallel with the front 75 wall of the combustion chamber.

75 The top side of the rear arch and the opposed under side of the top wall or roof of the combustion chamber define a passage leading from the space above the front end 80 portion of the grate to the combustion chamber, a gas inlet opening being provided in the front wall of the boiler chamber which extends between the rear end of the top wall or roof of the combustion chamber and the rear end of the arch.

85 The rear portion of the roof of the combustion chamber is arranged horizontally except for its extreme rear end which is curved in an arc to the inner side of the front wall of the boiler 90 chamber. The corresponding rear portion of the top side of the rear arch is inclined rearwardly and downwardly at a considerable angle so as to provide a rearwardly flaring expansion space between said corresponding rear portions of the roof and arch. The remaining portions of said walls of the 95 passage are arranged parallel and are inclined slightly downwardly and rearwardly except for the forward end portions thereof which are arranged horizontally. The height of the space between the bridge wall 100

and the chamber roof, except between the rear portions thereof, is substantially one-half the length of the space between the front wall of the combustion chamber and the front end of the rear arch.

With this arrangement, by admitting an excessive amount of air to the rear end portion of the grate, the low volatile gases generated beneath the rear arch are blown forwardly with sufficient velocity through the restricted space beneath the rear arch to cause them to thoroughly mix with the high volatile gases generated in the relatively large expansion space above the front end of the grate where the velocity of the gases is materially reduced, and thus cause complete combustion to take place in the combustion chamber at this point so that by the time the gases enter the boiler proper complete combustion has taken place. The fine particles of incandescent fuel that are blown into the stream of gas by the flow of air through the fuel bed are carried forwardly by the high velocity under the rear arch to the front end of the stoker where the gas velocity is reduced very materially as above described, which permits the particles to drop back upon the fuel bed at this point, thus materially aiding ignition and, of course, increasing the efficiency. With the standard furnace these fine particles would be blown into the ash pit.

The space between the top side of the rear arch and the roof of the combustion chamber is designed and shaped, and the gas velocity is high enough over the front portion of the rear arch to keep the top service of the rear arch swept clear of all fine ash and dust. This space or passage has a so-called Venturi effect, that is, the gases slow up as they reach the enlarged rear end of the passage and come nearer to the boiler, so that they will not impinge at too high a velocity against the boiler tubes, and also so as to give the fine ash carried in the gases time to precipitate or drop down upon the rear end portion of the top surface of the rear arch, at which point means may be provided for easily removing this fine ash.

Also, with this arrangement practically any percentage of CO_2 within practical limits can be maintained at the point where the gases enter the boiler by varying the amount of air admitted through the last or rearmost compartment of the stoker. It has been found that 17 per centum of CO_2 can be maintained continuously but the temperature at so high a percentage of CO_2 is excessive, causing the refractories to melt, but by admitting more air through the rearmost compartment, the CO_2 can be brought down to any desired point, and it has been found that from 14 to 15 per centum of CO_2 is as high as it is desirable to maintain.

With this construction of furnace it has

been found to be possible to burn very fine sizes of anthracite coal and at the same time obtain higher ratings and higher efficiencies than it has been possible to do heretofore, and in most cases it is possible to install 70 stokers where it would be impracticable to do so if a standard furnace only were available, and the cost in many instances is less than would be the case with a standard furnace.

In the illustrated construction the rear arch is made up of two walls 22 and 24 arranged one over the other and spaced a distance apart with their front and rear ends closed. Air under pressure is admitted 80 in the space thus provided between the two walls of the arch through a damper controlled opening 26 which may be in communication with any suitable source of compressed air supply. The air thus admitted 85 to this space is discharged through a duct 28 leading to one of the air supply compartments 8 of the stoker, preferably the forward one. This air in passing through the space between the two walls of the rear 90 arch cools the steel work and castings supporting the arch, and thus becomes pre-heated before it passes to the stoker compartment where it is utilized to support combustion. Such ventilating or cooling of the 95 rear arch is necessary because of the intense heat to which the arch is subjected on both sides thereof.

As will be evident to those skilled in the art, my invention permits various modifications without departing from the spirit thereof or the scope of the appended claim.

What I claim is:

A furnace of the class described having, in combination, a traveling grate, a boiler chamber at the rear of said grate, a front wall, a top wall arranged substantially horizontally and extending substantially over the length of the grate, and a rear arch extending over substantially one-half of the length of the grate and arranged in proximity thereto, the forward end of said arch being spaced a distance from said front wall to provide an expansion space, and the top side of said rear arch together with the opposed portion of said top wall providing a restricted passage leading from said expansion space to the boiler chamber, said arch being made up of two walls arranged one above the other and spaced a distance apart with the spaces between their ends closed, means for admitting air under pressure to said space between said walls of the arch, and means for discharging the air after passing through said space beneath the upper run of the grate to support combustion.

In testimony whereof, I have signed my name to this specification this 12th day of July, 1926.

CHRISTIAN SCHILLINGER.
